UNITED STATES PATENT OFFICE.

EARL W. AUER, OF LOUISVILLE, AND STEVENSON PASTORIUS, OF CANTON, OHIO, AS
SIGNORS TO CENTRAL ALLOY STEEL CORPORATION, OF NEW YORK, N. Y., A COR-
PORATION OF NEW YORK.

ROLLER-NOZZLE GUIDE FOR BAR MILLS.

Application filed January 20, 1923. Serial No. 613,915.

This invention relates to a roller nozzle guide for bar mills and more particularly to a guide of this character mounted upon the end of the usual pipe or tube, through which bars are customarily passed from the bar mill to the reel or drum, upon which the rolled bars are coiled.

The objects of the invention are to provide a roller nozzle guide over which the bars are passed as they come from the bar mill, to prevent scratching or roughening of the under surface of the bars.

The above and other objects may be attained by providing the usual pipe or tube in position to receive the rolled bars as they pass from the bar mill, the roller nozzle to which the invention pertains being mounted upon the outer end of the pipe or tube in a position to receive the bar as it passes from the tube to the usual reel or drum, upon which the rolled bars are coiled.

An embodiment of the invention is illustrated in the accompanying drawing, in which—

25 Fig. 1 is a longitudinal, sectional view showing a bar mill, pipe and reel of usual construction, the roller nozzle embodying the invention being illustrated upon the outlet end of the pipe;

30 Fig. 2, an end elevation of the roller nozzle; and

Fig. 3, a section on line 3—3, Fig. 2.

Similar numerals of reference indicate corresponding parts throughout the drawing.

Referring to Fig. 1, a bar mill is shown including the housing 1, rolls 2, rest bar 3 and guide 4, which may be of any usual construction. The usual pipe or tube 5 is shown supported in alignment with the guide 4 and provided with the funnel mouth 6, the rod 7 being shown passing through the bar mill in the direction of the arrow and entirely through the pipe or tube 5, after which it is coiled upon the usual reel or drum 8, mounted beyond the pipe.

This much of the construction is in general use where it is common practice to coil a rolled bar as it passes from the bar mill and forms no part of the present invention.

It has been found that in passing a bar from a bar mill through a pipe or tube of this kind, and coiling the same upon a reel or drum, the under side of the bar passing

over the edge of the pipe, at the point 55 where the bar leaves the pipe, is generally scratched or roughened, requiring considerable time and labor to repair the damage to the bar and causing considerable waste, as many of the bars are damaged beyond 60 repair.

The present invention has been devised to overcome this difficulty, and comprises the nozzle 9, preferably tapered toward its outer end. This nozzle may be provided at its inner 65 end with the internal screw threads 10 arranged to be mounted upon the threaded extremity 11 of the pipe or tube 5 and has the spaced, depending flanges 12 at its outer end portion between which is journaled a 70 grooved roller 13 journaled upon the bolt 14, the lower wall of the nozzle being removed between these flanges to receive the roller.

It will be seen that as the bar passes from 75 the bar mill, and through the tube or pipe 5 to the reel or drum, the under side of the bar will be supported upon the grooved roller 13 at the point where the bar leaves the pipe, thus preventing any scratching or 80 roughening of the bar and obviating the necessity of filing or otherwise repairing the bar, such as is necessary with the present practice of rolling and coiling bars.

Although the invention is illustrated as 85 applied to the extremity of the usual tube or pipe through which bars are passed to the reel or drum upon which they are coiled, it will be understood that the invention is applicable to other forms of bar mills where 90 the bars are not passed through a tube or pipe and after which coiled upon a reel or drum, as the roller nozzle may be supported in position to receive the bar directly from the guide of the bar mill, the bar being 95 passed through the nozzle and over the roller therein in the manner above described.

We claim:

1. In combination with a bar mill, a pipe 100 arranged to receive the bars as they pass from the bar mill and a reel upon which the bars are arranged to be coiled as they pass from the pipe, a roller at the extremity of the pipe upon which the bars are arranged to be supported as they pass to the reel.

2. In combination with a bar mill, a pipe 105 arranged to receive the bars as they pass

- from the bar mill and a reel upon which the bars are arranged to be coiled as they pass from the pipe, a nozzle mounted upon the extremity of the pipe and a roller in 5 the nozzle arranged to support the bars as they pass to the reel.
3. In combination with a bar mill, a pipe arranged to receive the bars as they pass from the bar mill and a reel upon which the 10 bars are arranged to be coiled as they pass from the pipe, a tapered nozzle mounted upon the extremity of the pipe and a roller in the nozzle arranged to support the bars as they pass to the reel.
4. A roller nozzle guide of the character 15 described, including a tapered hollow nozzle having a pair of spaced, depending flanges at its tapered end portion, and a roller journaled between said flanges.

EARL W. AUER.
STEVENSON PASTORIUS.
